UNITED STATES PATENT OFFICE.

ROBERT LAING, OF MIDDLETON, ENGLAND.

MACHINE FOR PRESSING LINES OR DESIGNS INTO ROLLERS.

1,414,574.

Specification of Letters Patent. Patented May 2, 1922.

Application filed May 29, 1920. Serial No. 385,381.

To all whom it may concern:

Be it known that I, ROBERT LAING, a subject of the King of Great Britain, residing at Middleton, in the county of Lancaster, England, have invented certain useful Improvements in a Machine for Pressing Lines or Designs into Rollers, of which the following is a specification.

This invention relates to improvements in machines for pressing lines or designs into rollers used for imparting a lustre or silky appearance to cotton fabrics of the type in which a knurling mill or series of knurling mills are employed as described in specification 10 belong to British Letters Patent No. 6176 of 1907, granted to me, which press the lines or design gradually into the roller.

The said type of machine comprises generally, a bed with bearings to support the roller to be operated upon, a slide on said bed rendered longitudinally movable by a screw-threaded spindle, a stand on the rear end of said slide having a head in which is mounted the rear end of a frame carrying 20 at its front end the knurling mill holder and a lever adapted to exert pressure on the knurling mill.

The object of the present invention is to improve the general construction of said type 30 of machine, to simplify the manipulation thereof and thereby render same more efficient than hitherto has been the case.

A machine constructed in accordance with this invention comprises chiefly pressure 35 levers which are each fulcrumed to said frame at a point between its front and rear end, means for balancing said frame, improved means for pressing said levers against the top of the knurling mill holder and the 40 knurling mill against the roller to be operated upon, means for regulating the pressure exerted by said lever, means for the rotary adjustment of said knurling mill holder, means for the angular adjustment of the 45 knurling mill in relation to the periphery of said roller and means for the continuous supply of lubricant to the knurling mill pivots and its bearing and also to said roller.

I attain these objects by the means illustrated in the accompanying drawings, in which—

Figure 1 is an end view, Figure 2 a plan, Figure 3 a front view of the knurling mill head of the machine. Figures 4 and 6 are 55 vertical sections and Figure 5 a plan of Figure 4, of the knurling mill holder. Fig-

ure 7 is a longitudinal section of the rod connection.

Similar letters and numerals refer to similar parts throughout the various views. 60

a is the bed of the machine, *b* the roller to be operated upon, *c* is the knurling mill, *d* the knurling mill holder, *e* the pressure lever, *f* the knurling mill head slide and *g* the rod connection between the said lever 65 and slide.

Referring to the figures generally, the pressure levers *e* are each fulcrumed to the knurling mill holder frame *h* at a point between its front and rear end and a lever *i* 70 is also fulcrumed to the frame *h* behind the fulcrum end of the pressure lever *e*. The frame *h* is rigidly connected at the rear to a pivot pin 22 which is pivotally mounted in the stand 23 in steps 24 the upper one of 75 which can be adjusted by the bolts 25. An adjustable counter weight *k* is provided on the lever *i* to counter-balance the weight of the frame *h* and the parts carried thereon. The pivot on the stand 23 enables the frame 80 *h* and the parts thereon to be lifted clear of the work and the lever *i* and counterweight *k* facilitate the lifting of the frame *h* and the lowering of the same into its correct working position in which it is rigidly secured by tightening the bolts 25 and thereby 85 clamping the pivot pin 22 between the steps 24. The pivot 22 therefore merely serves to raise the frame *h* and parts thereon clear of the work, and the counterweight *k* to reduce the effort necessary to perform this 90 operation after the bolts 25 have been slackened the pressure of the knurling mills *c* on the work being obtained by the hereinafter described means. 95

The pivoted lever *i* is prevented from falling by the bottom of the pivot end being made to abut against the base of the bracket to which it is pivoted.

The front end of each pressure lever *e* 100 and the front end of the slide *f* are coupled together by means of a spring influenced rod connection *g*, *l*, *m*, *n* formed in sections with ends suitably pivoted to the outer end of the pressure lever *e* and slide *f*. The 105 lower end of the top section *l* and the upper end of the middle section *m* are coupled together by means of a right and left hand threaded union nut *g*, see more particularly Figures 1 and 7, while the upper end of the 110 bottom section *n* has secured a cylindrical casing *o* at the top end provided with a

screw-threaded cap *p* through which the upper end of the middle section *m* extends and which section together with the bottom section *n* can be longitudinally adjusted by 5 the union nut *g* to either shorten or lengthen the rod connection and thereby vary the pressure of the pressure lever *e* on the knurling mill holder *d* as may be required for different work.

- 10 In the casing *o* is located around the middle rod section *m*, a coiled spring *q* supported by a shoulder *r* formed on the lower end of the latter and with its upper end bearing against the cap *p* on the casing *o* 15 which spring imparts in said rod connection a certain amount of longitudinal elasticity and on which cap rests loosely a distance collar *j* with which when the knurling mill leaves the roller surface of the lock nut *i* 20 contacts, which prevents the knurling mills dropping onto the roller ends and thus prevents same being damaged.

The middle rod section *m* is prevented from rotating by being formed with flats *s* 25 engaging in a correspondingly shaped hole *t* in the cap *p*.

The top section *l* is preferably pivotally connected with the outer end of said pressure lever *e* by providing its upper end with 30 a cross stud *u* adapted to engage in grooves *v* formed on the top of the respective end of the lever *e* preferably forked, while the bottom section *n* is connected to knurling mill slide *f* by means of an eye bolt *w* and 35 pin *x*.

The method described of pivoting the top end of said rod connection to the free end of the pressure lever and the fulcruming of the latter to said frame, permits of readily 40 connecting said rod connection from the pressure lever and also of removing the latter when required.

The periphery of the flange *z* at the upper end of the bush *y* located in the frame *h* is 45 formed with a worm wheel 2 arranged in gear with a worm 3 mounted on the frame *h* whereby the knurling mill *c* can be rotatably adjusted in relation to the periphery of the roller *b* as may be required and locked 50 in position by the set screw 4.

The top of the frame *h* is provided with a pointer 5 and the top of the bush *y* with a graduated circular scale 6 whereby the amount of the adjustment can easily be read 55 and thus readily determined.

To ensure the knurling mill *c* always operating with its periphery parallel with the periphery of the roller *b*, it is made angularly adjustable on the head of the 60 knurling mill holder *d* in order to permit compensating for any difference in the relative positions of either of said peripheries. This angular adjustment may be effected by forming the head of the holder in which the 65 knurling mill *c* rotates in two parts 9 and

10, the part 10 being pivoted to the part 9 say by a bolt 8, as in the present instance. The part 9 carries on each side of its stud 8 a set screw 7 adapted to bear against the top of the part 10 by means of which the 70 angle at which the knurling mill *c* is to rotate, can be readily varied.

To prevent the knurling mills *c* from leaving their bearings 13, when the head end is lifted or the knurling mills pass the roller 75 ends flat springs 11 are secured to the knurling mill head part 10 which bear against the knurling mill pivots 12 and thus support the knurling mills.

In order to permit of automatically supplying the knurling mill pivots 12 and bearings 13 and roller *b* to be operated upon, with lubricant, two superposed vessels 14, 15 are employed, the upper one 14 of which is suitably attached to front end of the frame 85 *h* and the lower one 15 to the front side of the knurling mill bearing or head 10. The latter vessel is arched to facilitate placing of the knurling mill *c* in the forked bearing 13 of the holder *d* and by a pipe 16 furnished with a tap 17 is connected with upper vessel 14. The lower vessel 15 has also two pipes 18 extending from the inner side thereof, fitting into correspondingly located holes 19 formed in one side of the forked bearing 13 leading to grooves 20 therein, while the bottom is furnished with pipe 21 extending to near the periphery of the roller *b* to be operated upon.

I claim:—

1. A machine for pressing lines or designs into rollers used for imparting a lustre or silky appearance to cotton fabrics, comprising a knurling mill head, a frame pivotally mounted thereon, a knurling mill holder carried by said frame, and pressure levers fulcrumed to said frame at a point between its pivot and front end, for the purpose specified.

2. A machine for pressing lines or designs into rollers used for imparting a lustre or silky appearance to cotton fabrics, comprising a knurling mill head, a frame pivotally mounted thereon, a knurling mill holder carried by said frame, pressure levers fulcrumed to said frame at a point between its fulcrum and front end, a rearwardly extending weighted lever fulcrumed to said knurling mill holder frame in front of its pivot for the purpose specified.

3. A machine for pressing lines or designs into rollers used for imparting a lustre or silky appearance to cotton fabrics, comprising a knurling mill holder frame having pressure levers fulcrumed thereto, a knurling mill head slide, a spring influenced rod connection between said pressure levers and the knurling mill head slide, for the purpose specified.

4. A machine for pressing lines or designs

- into rollers used for imparting a lustre or silky appearance to cotton fabrics, comprising a knurling mill holder frame having pressure levers fulcrumed thereto, a knurling mill head slide, a spring influenced rod connection between said pressure levers and the knurling mill head slide and means for regulating the tension of said spring influenced connection. 5
- 10 5. A machine for pressing lines or designs into rollers used for imparting a lustre or silky appearance to cotton fabrics, comprising a knurling mill holder frame having pressure levers fulcrumed thereto, a knurling mill head slide, a spring influenced rod connection between said pressure levers and the knurling mill head slide, said spring influenced connection being formed in three sections with the adjacent end of the upper 15 and middle sections coupled together and longitudinally adjustable in relation to each other and the lower end of the middle section having a shoulder, a coiled spring on said shoulder supporting the bottom section, 20 for the purpose specified.
6. A machine for pressing lines or designs into rollers used for imparting a lustre or silky appearance to cotton fabrics, comprising a knurling mill head, a frame fulcrumed thereto, a bush in said frame, a knurling mill holder rotatively and vertically slidably connected with said holder, a worm wheel adapted to rotate with said bush and a worm in gear therewith mounted on the 35 holder, for the purpose specified.
7. A machine for pressing lines or designs into rollers used for imparting a lustre or silky appearance to cotton fabrics, comprising a knurling mill head, a frame fulcrumed thereto, a bush in said frame, a knurling mill holder in said bush rotatable with said bush, a pointer on said frame and a circular graduated scale on the said bush adjacent 40
- end to said index finger, for the purpose specified. 45
8. A machine for pressing lines or designs into rollers used for imparting a lustre or silky appearance to cotton fabrics, comprising a knurling mill head, a frame fulcrumed thereto, a knurling mill holder carried by 50 said frame and means for causing the angular adjustment of the knurling mill on the holder relative to the periphery of the roller to be operated upon, said means consisting of a knurling mill bearing fulcrumed 55 to the knurling mill holder and of a set screw in the knurling mill holder at each side of the respective fulcrum adjustable against said knurling mill bearing, for the purpose specified. 60
9. A machine for pressing lines or designs into rollers used for imparting a lustre or silky appearance to cotton fabrics, comprising a knurling mill head, a frame fulcrumed thereto, a knurling mill holder carried by 65 said frame having bearing for the knurling mill and means for continuously lubricating said bearings and the periphery of the roller to be operated upon, said means consisting of an oil feed vessel for each knurling mill 70 holder head having near the bottom two pipes entering holes in the knurling mill holder head, a pipe leading to the periphery of said roller and a joint oil supply vessel, a pipe leading from the said supply 75 vessel to feed vessel furnished with a tap for the control of the lubricant from the former to the latter vessel, for the purpose specified.

Signed at Manchester, England, this 14th 80
day of May, 1920.
